UNITED STATES PATENT OFFICE

2,549,990

LOADING ELEVATOR FOR BALES, CRATES,
AND THE LIKE

Edgar H. Skelton, Blackwell, Okla.

Application November 25, 1947, Serial No. 787,991

1 Claim. (Cl. 198—233)

1 The present invention relates to new and useful improvements in loading elevators and more particularly to a loading elevator for baled hay and similar bulk materials.

An important object of the present invention is to provide a trailer frame on which the elevator is carried and providing a power plant carried directly by the elevator for operating the same and manually operated means for vertically adjusting the delivery end of the elevator.

A further object is to provide an apparatus of this character of simple and practical construction, which is strong and durable, efficient and reliable in operation, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a top plan view.

Figure 2 is a side elevational view showing the elevator in its lowered position when not in use.

Figure 3 is a similar view showing the elevator in its raised position.

Figure 4 is a vertical transverse sectional view taken substantially on the line 4—4 of Figure 3, and

Figure 5 is an enlarged fragmentary sectional view taken on a line 5—5 of Figure 3.

Referring now to the drawings in detail wherein for the purpose of illustration I have disclosed a preferred embodiment of the invention the numeral 5 designates a trailer frame to one end of which an axle 6 is secured with the wheels 7 journalled on the ends of the axle. The other end of the frame is provided with a tractor hitch 8 of conventional construction and by means of which the trailer may be detachably connected to a draw-bar 9 of a tractor or other towing vehicle.

The front end of the frame 5, adjacent the hitch 8 is provided at its side edges with upstanding supports 10 suitably braced as shown at 11. The receiving end of a loading elevator frame 12 is pivoted to the upper end of the support 10 by pins or the like 13 for vertical swinging movement of the delivery end of the elevator.

The elevator 12 extends longitudinally above the frame 5 with its delivery end projecting rearwardly of the wheels 7, the elevator being substantially balanced on the wheels.

The elevator frame 12 includes spaced parallel

longitudinally extending frame members 14 suitably braced as shown at 15, the side frame members having side rails 16 supported in an elevated position thereon by posts 17 and braces 18. Positioned between the side frame members 14 are substantially flat spaced parallel tracks 19, the tracks being suitably secured to the cross bracing 15.

2 A front transverse shaft 20 is journalled at the front ends of the side frame members 14 and a rear transverse shaft 21 is journalled at the rear end of the side frame members 14. A sprocket 22 is carried by the shaft 20 and a sprocket 23 is secured to the shaft 21, the sprocket having an end less conveyor chain 24 trained thereon. The chain 24 is driven by the sprocket 23 and shaft 21 by means of an electric motor 25 supported on a bracket 26 beneath the rear end of one of the side frame members 14, the motor driving the shaft 21 through a series of belts or chains 27 and reduction pulleys or sprockets 28.

A plurality of conveying lugs or prongs 29 are suitably secured at longitudinally spaced intervals to the chain 24 whereby bales of hay or other material deposited on the elevator at the receiving end thereof will be conveyed longitudinally of the elevator.

An idler sprocket 30 is suitably supported beneath the elevator 12 over which the lower flight of the chain travels to remove slack therein.

A pair of arms 31 are provided with collars 32 at their front ends for pivotally mounting the arms on the axle 6, the arms being connected to each other for uniform raising and lowering movement by cross members 33. Grooved rollers 34 are journalled at the rear ends of the arms to travel under the lower edges of the frame members 12.

A cable 35 is secured at one end to the rear end of one of the arms 31 and extends forwardly under the elevator for winding and unwinding on a drum 36 secured to a shaft 37 journalled at the front end of trailer frame 5 and manually operated by a handle 38 and gears 39.

A pair of props 40 rise from the axle 6 having reduced vertical pins 41 at their upper ends to enter recesses 42 in the underside of frame members 12 to support the elevator in a lowered substantially horizontal position on the trailer when not in use and while being transported from place to place.

In the operation of the device, the rear or delivery end of the elevator is raised or lowered into a desired vertically adjusted position by the drum 36 and cable 35 and bales of hay 43 or other ma-

aterial received on the lower front end of the elevator is conveyed rearwardly by the motor driven chain 24 and delivered at its upper end for storage or stacking.

In view of the foregoing description taken in conjunction with the accompanying drawings it is believed that a clear understanding of the construction, operation and advantages of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claim.

Having described the invention what is claimed as new is:

A portable loading elevator comprising a two-wheel trailer including an axle and a frame extending forwardly therefrom, an endless conveyor including a frame pivoted at its front end to the front end of the trailer frame and having recesses at its underside, props rising from the axle and supporting the conveyor frame in its

lowered position, upstanding pins on the upper ends of the props and adapted to enter said recesses to hold the frame laterally centered on the axle when the frame is lowered and means carried entirely by the trailer for vertically adjusting the free end of the conveyor.

EDGAR H. SKELTON.
